PROGRAM CONTROL PANEL

Filed June 28, 1937

Inventor:
Lloyd J. Andres
By Kent W. Wonnell Atty.

UNITED STATES PATENT OFFICE

105,786

DESIGN FOR A PROGRAM CONTROL PANEL

Lloyd J. Andres, Chicago, Ill., assignor to Automatic Instrument Company, Grand Rapids, Mich., a corporation of Michigan

Application June 28, 1937, Serial No. 70,084

Term of patent 14 years

To all whom it may concern:

Be it known that I, Lloyd J. Andres, a citizen of the United States of America, and resident of the city of Chicago, in the county of Cook and State of Illinois, have invented a new, original, and ornamental Design for a Program Control Panel, of which the following is a specification, reference being had to the accompanying drawing, forming part thereof.

The figure is a front perspective view of a program control panel, showing my new design.

I claim:

The ornamental design for a program control panel as shown.

LLOYD J. ANDRES.
